UNITED STATES PATENT OFFICE

PASCO SAMMARTINO, OF PROVIDENCE, RHODE ISLAND

FINGER-RING

Application filed January 15, 1931. Serial No. 508,987.

This invention relates to improvements in ornamental finger-rings, and particularly to rings having settings for jewels, gems or precious stones.

5 One object of the invention is to provide a ring of solid, massive appearance while economizing in the use of precious metal embodied therein so as to reduce the cost of the article.

10 Another object of the invention is to provide a ring of substantially hollow construction to reduce the weight of the precious metal embodied therein, yet having every appearance of a solid ring.

15 Another object of the invention is to provide a ring of the type specified which may be manufactured from a plurality of interfitting sections constructed from sheet-metal stampings produced in dies.

20 Further objects of the invention are set forth in the following specification which describes a preferred form of construction of the improved ring, by way of example, as illustrated by the accompanying drawings. In 25 the drawings:

Fig. 1 is an enlarged side elevation of a finger-ring constructed in accordance with the present invention;

Fig. 2 is a similar enlarged view showing 30 the upper portion of the ring and the jewel-setting in vertical section;

Fig. 3 is a cross-sectional view of the ring taken on line 3—3 of Fig. 2;

Fig. 4 is a perspective view of the main or 35 base section of the ring;

Fig. 5 is a perspective view of the outer shell which encloses the gem-setting at the top of the ring;

Fig. 6 is a perspective view of the inner 40 bezel for the gem-setting;

Fig. 7 is a perspective view of the outer rim or cover for the gem-setting;

Fig. 8 is a perspective view of one of the ornamental pieces employed to cover the 45 joints on the sides of the ring; and

Fig. 9 is a cross-sectional view similar to Fig. 2 showing a slightly modified form of construction of the ring.

The present improved finger-ring is constructed from a plurality of performed sec-

tions struck up from sheet-metal and shaped in suitable dies, with the parts assembled in overlapping, interfitting relationship to provide a hollow structure with a gem-box or jewel-setting at the top. The parts are assembled in permanent relationship to provide a unitary structure by soldering or otherwise securing the several sections together.

The improved ring may be constructed in any preferred ornamental shape or configuration, Fig. 1 illustrating it as taking the form of a massive gentleman's ring having a sloping-sided gem-box at the top for holding a precious or semi-precious jewel.

In the present embodiment of the invention 65 the improved ring is composed of four principal parts or sections, the base section 2 being of annular shape as illustrated in Fig. 4 and provided with an upstanding flanged wall 3 at its top forming the inner lining of 70 the gem-box. The base section 2 of the ring may be stamped from sheet-metal and shaped in dies to provide side shanks 4 which are continued downwardly to form an annular portion having the opposite ends abutting 75 and soldered together at 5 (see Fig. 2). The annular portion of the ring is narrow at the bottom with the shanks 4 widened at the top to merge into a relatively broad arcuate base 6, from which rises the wall 3. The wall 3 80 may be of generally octagonal shape in edge view to conform more or less to the contour of the gem or jewel held in the setting, and preferably its flat side-faces converge towards the top. The metal of the upper portion 6 of the ring is reduced in thickness extending down onto the shanks 4 at its sides, thus forming projecting shoulders 7 as shown most clearly in Figs. 2 and 4.

Adapted to fit over the reduced upper portion of the main section 2 of the ring is an outer shell 10, shown in perspective view in Fig. 5. The shell 10 has substantially flat wedge-shaped side portions 11 which overlap the reduced shanks 4 on the sides of the 95 main section 2 with their lower ends fitted against the opposite shoulders 7 and the sides conforming to the generally circular shape of the annular bottom portion of the ring. The shell 10 is of substantially box-shape at its 100

top having flat sides 12, 13, etc., corresponding substantially to the flat faces of the inner flanged wall 3 and adapted to surround the latter in spaced relation thereto, see Figs. 5 2 and 3. The bottom edges of these flat faces of the shell 10 are shaped to conform to the circular contour of the upper reduced portion 6 of the main section 2 of the ring to adapt them to be soldered thereto with a 10 close smooth seam at the joinder of the parts.

The inner bezel 15, shown in perspective view in Fig. 6, is of generally octagonal shape having sloping sides corresponding to the flat faces of the flanged wall 3 on the 15 main section 2 of the ring. This section of the ring is placed across the upper edge of the flange 3 to form a seat for the jewel 17, being soldered to be inside of the section 18 before the parts are assembled. To secure 20 the jewel in the setting a cover or rim-section 18 is provided, its sides conforming to the flat sides of the shell 10 to adapt its lower edges to be soldered thereto. In effect, the section 18 forms a continuation of the shell. 25 10 with its sides having the same general contour. The upper rim of the section 18 is adapted to be swaged over the edge of the jewel 17 to secure the latter in the setting in the manner as usually provided in rings 30 of the present type.

The several sides of the shell 10 and its extension 18 may be ornamented by embossing the metal in the dies in which it is formed, or by engraving suitable designs 35 thereon as indicated in the drawings.

To provide a smooth finish on the sides of the shanks of the ring small triangular pieces 20 may be soldered over the joints where the bottom edges of the portions 11 40 of the shell 10 abut the shoulders 7 on the main section 2.

Fig. 9 of the drawings illustrates a modified form of construction of the ring wherein the shell 10 and the upper cover or rim for 45 the gem-mounting are made integral in one stamping. In this way the structure is simplified and the number of manufacturing operations reduced.

With either form of construction the improved ring has a massive, substantial appearance and cannot be distinguished from a heavy, solid ring. Its hollow construction, however, results in a very considerable saving of the precious metal from which it is 55 made and therefore renders it relatively low in cost. When the ring is made from silver or gold it may be marked "sterling" or with the "karat", as the case may be, and thus may be marked in competition with solid rings at 60 a much lower price.

The parts from which the ring is constructed may be struck up in dies, thus further economizing in the cost of manufacture, and the invention is therefore of great advantage 65 in the art to which it relates.

While the improved ring is herein shown and described as embodied in a preferred form of construction and as comprising a gem-setting, it is to be understood that modifications may be made in its form and design 70 without departing from the spirit or scope of the invention as expressed in the appended claims.

I claim:

1. A finger-ring comprising a main annular section having an opening in the top surrounded by an upstanding wall, a shell shaped substantially to the contour of the upper portion of the annular section and secured thereto with its upper sides surrounding the upstanding wall thereof in spaced relation thereto, and a section overlying the upstanding wall to close the opening between the parts to provide a hollow structure giving 75 the appearance of a solid ring.

2. A finger-ring comprising a main annular section having its upper portion extended to form a relatively wide base with an opening at its center and a wall projecting upwardly from the margin thereof, a shell section having its upper portion shaped substantially to the shape of the upstanding wall on the main section and surrounding the latter in spaced relation thereto, the sides of said shell extending down onto the shanks 80 of the annular section and being secured thereto at the edges, and a section extending across the opening between the inner wall and the shell whereby to provide a hollow structure giving the appearance of a solid ring. 85

3. A finger-ring comprising a main annular section having a widened top with a central opening therein and a wall rising from the margin thereof, a shell enclosing the wall 90 on the annular section with its side arranged in opposite spaced relation thereto and joined to the edges of the upper part of the annular section, a bezel overlying the inner wall of the main section of the ring to adapt it to receive a jewel or other ornament, and a flange at the top of the shell adapted to be bent over the edges of the jewel to hold it in 95 place in the setting. 100

4. A finger-ring comprising an annular section having its upper portion widened and formed with a central opening with a marginal wall rising therefrom, a shell having sides conforming to the sides of the upstanding wall on the main section and surrounding the latter in spaced relation thereto with its edges secured to the upper part of the annular section and its sides sloping outwardly from the top, and a bezel fitted across the upper edge of the inner marginal wall on the 110 main section to adapt it to receive a jewel and secured to the interior of the shell, the upper portion of the shell having a flanged rim adapted to overlie the edges of the jewel to hold the latter in place in the setting. 115

5. A finger-ring comprising a main annular section having an upper widened portion with tapering shanks and a central opening bounded by an upstanding wall, the
5 upper portion of the annular section being reduced in thickness to provide shoulders at its sides, an outer shell having its sides shaped substantially to the shape of the upstanding wall and arranged in spaced relation
10 with respect thereto, the opposite sides of the shell extending downwardly along the reduced shanks of the main section with their lower ends abutting the shoulders thereon, the edges of said shell being secured
15 to the edges of the upper annular portion of the main section, and means at the top for closing the space between the shell and the inner upstanding wall to form a hollow structure having substantially the appearance of
20 a solid ring.

6. A finger-ring comprising a main annular section having its upper portion widened and connected to the lower portion in tapered shanks, the upper portion of the main
25 section being reduced in thickness forming shoulders at the sides and formed with an enlarged opening at the top having a marginal wall extending upwardly therefrom, an outer shell having sides conforming substantially to the sides of the upstanding wall on the main section and surrounding the latter in spaced relation with respect thereto, the edges of the shell being joined to the edges
30 of the upper portion of the main section and having its sides merging into the shanks thereof and meeting the shoulders thereon, ornamental sections covering the joints between the shell and the shanks of the main section, and a bezel resting across the edge
35 of the upstanding wall on the main section and secured to the inner wall of the shell.

40 In testimony whereof I hereunto affix my
signature.

45 PASCO SAMMARTINO.
